US0D1112262S

(12) **United States Design Patent** (10) **Patent No.:** **US D1,112,262 S**
Mitchell et al. (45) **Date of Patent:** **** Feb. 10, 2026**

(54) **DISPLAY SCREEN OR A PORTION THEREOF WITH A GRAPHICAL USER INTERFACE**

(71) Applicant: **Lincoln Global, Inc.**, Santa Fe Springs, CA (US)

(72) Inventors: **Levi J. Mitchell**, Windsor, CO (US); **Jacob F. Aas**, Windsor, CO (US); **Camila Maria Perez Gavilan Torres**, Kitchener (CA); **Taylor L. Robertson**, Kitchener (CA); **Jeffrey T. E. Dugan**, Waterloo (CA); **Connor S. Sweet**, Waterloo (CA)

(73) Assignee: **LINCOLN GLOBAL, INC.**, Santa Fe Springs, CA (US)

(**) Term: **15 Years**

(21) Appl. No.: **29/894,299**

(22) Filed: **Jun. 8, 2023**

(51) LOC (15) Cl. **14-04**

CLAIM

The ornamental design for a display screen or a portion thereof with a graphical user interface, as shown and described.

DESCRIPTION

The FIGURE is a front view of a display screen or a portion thereof with a graphical user interface.

The peripheral dot-dashed broken lines depict the display screen or portions thereof that form no part of the claimed design. The dashed broken lines depict portions of the graphical user interface that form no part of the claimed design.

1 Claim, 1 Drawing Sheet
